United States Patent Office

Des. 195,757
Patented July 30, 1963

195,757

SHOE SOLE OR SIMILAR ARTICLE

Alan Beverley Lewis, Beaconsfield, Quebec, Canada,
assignor to The British Rubber Company Limited,
Lachine, Quebec, Canada

Filed Dec. 7, 1962, Ser. No. 72,757

Term of patent 14 years

(Cl. D7—5)

I claim:

The ornamental design for a shoe sole or similar article, as shown.
